R. E. COTTERMAN
APPARATUS FOR THE SEPARATION OF VOLATILE PRODUCTS FROM
SOLID CARBONACEOUS MATERIAL
Filed Aug. 20, 1925

By *Clarance A. O'Brien*

Attorney

UNITED STATES PATENT OFFICE.

ROY EBY COTTERMAN, OF FARMERSVILLE, OHIO.

APPARATUS FOR THE SEPARATION OF VOLATILE PRODUCTS FROM SOLID CARBONACEOUS MATERIAL.

Application filed August 20, 1925. Serial No. 51,392.

The present invention appertains to the art of separation of volatile products from solid carbonaceous material, and has for its purpose to separate from shale rock by heating, crude oil, and all the by-products of ammonium sulphate, potash, etc. and to recover from spent shale the dye stuff, paint fillers, etc.

The object of the invention is to provide a construction which is both simple and durable as compared with the intricate apparatus now in common use.

Another important object of the invention is to provide an apparatus which is exceedingly efficient and reliable in its operation, and is able to withstand the intense heat necessary in the cooking process.

With the apparatus now in use it is necessary, every five or six weeks, to replace important parts at a high cost, whereas the present invention obviates these periodical costs and consequently reduces the upkeep. This end is accomplished by the introduction of a non-warping steel cylinder or cylindrical tank which, in actual practice, has withstood a heat of fifteen hundred degrees Fahrenheit without warping or burning.

With the above and numerous other objects in view as will appear as the description proceeds the invention resides in certain novel features of construction, and in the combination and arrangement of parts as will be hereinafter more fully described and claimed.

In the drawing:—

The figure is a longitudinal vertical section through the apparatus.

Referring to the drawing in detail it will be seen that A indicates generally the retort, having mounted therein the usual burner B, and extending upwardly therefrom the usual stack C. A retort cylinder 5 is mounted across the top of the retort A and is provided with the gas escape openings or conduits 6 which will lead to suitable condensing apparatus (not shown) but which is well known in this art. This cylinder 5 is made of steel of such a quality as to be non-warping in spite of the intense heat to which it is subjected. The burner B, of course, is located immediately below the cylinder, and extends longitudinally thereof. A shaft 7 is journaled longitudinally of the cylinder 5, and projects beyond the end thereof. One end of the shaft 7 is operatively connected

with a prime mover 8 through a chain 9. A funnel 10 leads into a cylindrical casing 11. In the upper end of the funnel 10 there is rotatably mounted a valve 12 of cylindrical formation having an opening 13 adapted to be brought into registry with the lower end of the hopper 14. The shaft 15 of the valve 12 is operatively connected with the shaft 7 by a chain 16. The shale is conveyed into the hopper 14 in any suitable manner, and when the opening 15 registers therewith, the shale will pour into the valve, and as the valve rotates, the shale poured thereinto will empty into the funnel 10, and pour into the cylindrical casing 11. A screw conveyor 17 is rotatably mounted in the cylindrical casing 11 which terminates within the tank 5, having an opening in the bottom of its communicating end as at 18. The shaft of the screw conveyor 17 is operatively connected with the shaft 15 by a chain 19. Thus it will be seen that the shale delivered to the cylindrical casing 11 will be conveyed by the screw 17 into one end of the cylinder 5. A plurality of spokes 20 radiate from the shaft 7 in a spiral alignment, and have paddles 21 mounted on the ends thereof and extending obliquely to the shaft 7. As the shaft 7 is rotating the shale is picked up from the bottom of the cylinder 5 by these paddles, and caused to circulate about the interior surface thereof, at the same time being urged toward the outlet end of the tank. The shale from the tank 5 is finally poured through the opening 23 into the cylindrical casing 24 communicating with a hopper 26. A screw conveyor 27 is rotatable in the casing 24 and extends longitudinally thereof so that the shale delivered to the casing 24 is conveyed so as to pour into the hopper 26. The shaft of the screw conveyor 27 is operatively connected by a chain 28 to the shaft 7. A valve 29, similar to valve 12, is rotatable in a casing 30 at the lower end of the hopper 26, and delivers the residue of the shale into the exhaust conduit 31. The shaft 32 of the valve 29 is operatively connected with the shaft 7 by a chain 33.

The vapors formed by the heating process, as the shale passes through the tank 5 pass off through the conduits 6, and are condensed as petroleum or crude oil in any well known manner. By the use of this apparatus, I have found that in running number 66 shale through the retort, I ob-

tain an average of sixty gallons to the ton, while the Government test only obtains forty-two gallons per ton, this experiment was by weight and liquid measure.

5 It is thought that the construction, operation, and advantages of this invention will now be clearly understood by those skilled in this art without a more detailed description thereof. The present embodiment of
10 the invention has been disclosed by way of example since in actual practice it attains the features of advantage enumerated as desirable in the statement of the invention and the above description. It will be apparent that changes in the details of construction, and in the combination and arrangement of parts may be resorted to without departing from the spirit or scope of the invention as hereinafter claimed or sacrificing any of its advantages.

Having thus described the invention, what I claim as new is:

1. An apparatus of the class described, including a retort comprising a burner, a cylinder extending across the top of the retort above the burner, and having gas escape conduits leading therefrom, a cylindrical casing leading into the upper portion of one end of the cylinder, and having a pair of
25 openings, one at the bottom thereof, interiorly of the cylinder, and the other at the top thereof, exteriorly of the cylinder, a funnel rising from said other opening, a valve of cylindrical formation and having an opening, said valve being rotatably mounted in the upper portion of the funnel, a hopper rising from the funnel, conveyor mechanism in the cylinder, and means for simultaneously operating the valve and the conveyor
30 mechanism.

2. An apparatus of the class described comprising a retort comprising a burner, a cylinder extending across the top of the retort above the burner and having gas escape
35 conduits leading therefrom, a cylindrical casing leading into the upper portion of one end of the cylinder, and having a pair of openings, one at the bottom thereof inter-

riorly of the cylinder, and the other at the top thereof exteriorly of the cylinder, a screw conveyor rotatably mounted in the cylindrical casing, a funnel rising from said other opening, a valve of cylindrical formation and having an opening, said valve being rotatable in the upper portion of the funnel, a hopper rising from the funnel, conveyor mechanism in the cylinder, and means for simultaneously operating the conveyor mechanism, the screw conveyor and the valve.

3. An apparatus of the class described including a retort comprising a burner, a cylinder extending across the top of the retort above the burner and having a gas escape conduit leading therefrom, a cylindrical casing leading into the upper portion of one end of the cylinder and having a pair of openings one at the bottom thereof interiorly of the cylinder, and the other at the top thereof exteriorly of the cylinder, a screw conveyor rotatably mounted in the cylindrical casing, a funnel rising from said opening, a valve of cylindrical formation and having an opening, said valve being rotatable in the upper portion of the funnel, a hopper rising from the funnel, conveyor mechanism in the cylinder, a second cylindrical casing at the lower portion of the other end of the cylinder and having a pair of openings, one at the bottom thereof exteriorly of the cylinder, and the other at the top thereof interiorly of the cylinder, a hopper leading downwardly from said other opening of the second cylindrical casing, a screw conveyor rotatably mounted in said second cylindrical casing, a valve of cylindrical formation and having an opening, said second mentioned valve being rotatable in the lower portion of the second mentioned hopper, and means for simultaneously operating the conveyor mechanism, the two screw conveyors, and the two valves.

In testimony whereof I affix my signature.

ROY EBY COTTERMAN.
